CALIFORNIA.

HYDROCARBON-BURNER.

1,324,755.

Specification of Letters Patent.

Patented Dec. 9, 1919.

Application filed December 16, 1918. Serial No. 267,055.

To all whom it may concern:

Be it known that we, JAMES TEWSLEY and RALPH D. HORTON, both citizens of the United States, residing in the cities of Long Beach and Los Angeles, respectively, in the county of Los Angeles and State of California, have invented new and useful Improvements in Hydrocarbon Burners, of which the following is a specification.

10 Our invention relates more specifically to a hydro-carbon burner construction adapted to be operated by cheap and inexpensive fuels, such as kerosene, distillates, and like hydro-carbon fractions.

15 An important object is to provide a burner construction in which the flow of gaseous mixture is evenly controlled, and in which the pressure in the burner tubes is efficiently equalized.

20 A further object is to provide a construction in which a portion of the generated gaseous mixture for the operation of the burner is stored, the stored portion being utilized to prevent any fluctuations in the 25 flow of said mixture in the burner tubes, and also to prevent "back firing" during its operation.

Other objects and advantages will be apparent from the following description, the 30 drawing clearly illustrating the construction:

Figure 1— is a plan view of our burner with parts broken away to disclose the interior construction.

35 Fig. 2— is a central longitudinal section taken on line 2—2 of Fig. 1.

Fig. 3— is a transverse section taken on line 3—3 of Fig. 1.

Referring more specifically to the drawings our improved burner preferably consists of a manifold gas inlet chamber 5, an equalizing manifold chamber 6, connected to each other by a plurality of burner tubes 7 each provided with a plurality of burner 45 slots 8. The size of the burner being such that it will afford easy placement in a stove or range construction of usual form.

The ends of the burner pipes 7 project into the interior of the manifold chambers, 50 as clearly shown in Figs. 1 and 2 of the drawing, so that the flow of gaseous mixture into the burner pipes will not be direct, but will be retarded slightly and thus create a more even pressure or flow into the burner 55 pipes.

Manifold chamber 5 is provided in its top wall and at the center thereof with a gas inlet opening 9, communicating with one end of a gas mixing pipe or chamber 10, the free end of said pipe extending 60 toward the center of the burner and terminating between and below the burner pipes 7, the end of the pipe being provided with a damper 11 of usual construction to regulate the admission of air to the mixing chamber. 65 Chamber 10 is provided with an opening 12 into which projects the discharge end of a gas generator 13, the end of said pipe being preferably disposed approximately in the center of the inlet opening of the mixing 70 chamber so that the gas and air will be efficiently mixed before entering the inlet chamber of the burner. By disposing the mixing chamber directly above the gas burner pipes the mixing chamber will be 75 efficiently heated during the operation of the burner and thus highly increase the combustibility of the mixture before it enters the inlet manifold chamber for distribution to the burner tubes. 80

Generator 13 is of usual construction, and preferably consists of a pipe 14 in which is mounted a plurality of wires 15 which serve to break up the fuel so that the gases will be quickly liberated on a heating of the 85 generator. The outer end of said generator is closed by a cap 16 provided with a centrally disposed gas outlet orifice 17, the other end of the generator being connected to a source of fuel supply (not shown) 90 which is preferably fed to said generator under pressure. Secured to or formed integral with the upper wall of manifold equalizing chamber 6 is a forked support 18 in which rests the outer end of the generator. 95

Secured to and projecting inwardly from the inner side wall 19 of the manifold equalizing chamber 6 is a gas supply pipe 20, provided on the upper surface with an elongated firing pan 21 containing the usual 100 asbestos wicking 22, by means of which the burner is put into operation. The supply pipe 20 is provided with a plurality of burner slots 23 that direct the flames against the generator during the operation of the 105 burner.

In the construction illustrated in the drawings two pairs of slotted burner tubes 7 are shown, a pair on each side, but a larger number of tubes may be used in producing 110

a construction that will quickly and efficiently heat the largest range or stove, it only being necessary when employing a larger number of tubes to increase the area 5 of the manifold gas chambers.

From the above description it is thought that no difficulty will be encountered in understanding the operation of our burner. Enough oil is introduced into the firing pan 10 21 which is then lighted so as to heat the generator 13, oil being admitted to the generator from the storage tank by means of a valve (not shown). When the burner begins to generate gas the damper 11 is 15 opened slightly to admit the proper amount of air to the mixing chamber and the gaseous mixture flows forwardly and downwardly through the mixing chamber into the manifold inlet chamber 5, the gas in 20 the chamber entering the burner tubes and passing therethrough to the equalizing chamber 6. It has been found in practice that the generator will generate a larger quantity of gas than can be utilized by the 25 burner tubes and all excess gaseous mixture that is not consumed in the passage through the burner tubes is stored in the chamber 6, the gas pressure thus created in the chamber 6 equalizing the pressure in 30 the burner tubes. By this arrangement it will be noted that the size of the flames issuing through the burner slots 8 of the burner tubes will be of the same size throughout their length, the pressure being 35 efficiently equalized. Also it will be noted that by such equalization no fluctuation of the flames issuing from the tubes will occur and all danger of "back firing" obviated. It will also be observed from the fore- 40 going that by means of the gas equalizing chamber 6 that greater pressure of the gas will be formed in the outer end of the gas supply pipe 20, the flames issuing from the outer end of said pipe impinging directly 45 against the outer end of the generator tube.

What we claim is:

1. A hydro-carbon burner construction, comprising a gas manifold chamber having a gas inlet opening leading thereto, a gas 50 manifold equalizing chamber, a plurality of apertured burner tubes connecting said

chambers, a gas mixing chamber connected to the inlet opening of the gas manifold chamber, said mixing chamber being located above and between said burner tubes, where- 55 by the chamber will be maintained in a heated condition during the operation of the burner, said chamber having an air inlet leading thereto, and a gas generator mounted above said burner tubes, the discharge 60 end of said generator terminating within said mixing chamber.

2. A hydro-carbon burner construction, comprising a gas manifold chamber having a gas inlet opening leading thereto, a gas 65 manifold equalizing chamber, a plurality of apertured burner tubes connecting said chambers, a gas mixing chamber disposed above said burner tubes, one end of said chamber communicating with the gas inlet 70 opening formed in said gas manifold chamber, the other end of said mixing chamber being open to the atmosphere and provided with a controlling damper, a generator tube mounted above said burner tubes, the discharge end of said generator terminating 75 within said mixing chamber, and an apertured gas supply pipe having a closed outer end connected to said equalizing chamber, said pipe provided with a firing pan and 80 located beneath said generator tube.

3. A hydro-carbon burner construction, comprising a gas manifold chamber having a gas inlet opening leading thereto, a gas manifold equalizing chamber, a plurality of 85 apertured burner tubes connecting said chambers, a gas mixing chamber connected to the inlet opening of the gas manifold chamber, said mixing chamber being located above and between said burner tubes, 90 said mixing chamber having an air inlet leading thereto, a damper for controlling said air inlet opening, and a gas generator mounted above said burner tubes, the discharge end of said generator terminating 95 within said mixing chamber.

In witness that we claim the foregoing we have hereunto subscribed our names this 26th day of November, 1918.

JAMES TEWSLEY.
RALPH D. HORTON.
